UNITED STATES PATENT OFFICE.

ROY E. HARDY, OF NEW YORK, N. Y.

ELECTRIC IGNITING DEVICE.

No. 884,731.

Specification of Letters Patent. Patented April 14, 1908.

Application filed December 18, 1905. Serial No. 292,178.

To all whom it may concern:

Be it known that I, ROY E. HARDY, a citizen of the United States of America, residing at New York city, in the county of New York and State of New York, have invented certain new and useful Improvements in Electric Igniting Devices, of which the following is a specification, reference being had therein to the accompanying drawings.

10 This invention relates to that type of electrical igniters in which an induction coil is used to produce a jump spark for firing charges in internal combustion engines on the interruption of a current passed through 15 its primary or low tension circuit.

The object of my invention is to combine the induction coil and a sparking plug in a single structure in such a manner that it is of compact shape, durable and efficient in 20 operation and easy to mount and dismount from the engine.

To this end my invention consists in the peculiar construction, arrangement and operation of different parts all as more fully 25 hereinafter described and shown in the accompanying drawings, in which

Figure 1, is a vertical central section, and Fig. 2, is a cross section on line x—x of Fig. 1. A and B represent diagrammatically the 30 primary and secondary of an induction coil which may be of any known construction and C represents an outer inclosing tubular casing preferably of insulating material in which the induction coil is secured. This 35 casing has secured to its closed end the binding posts a b to which the terminals of the primary circuit are secured and with which the terminals of the primary of the induction coil are electrically connected.

40 D represents the exterior metallic shell of a spark plug and constituting one of the electrodes thereof. It is provided with the usual screw-threaded portion c adapted to be screwed into a correspondingly threaded 45 opening in the cylinder of the engine, and with an enlarged head d which fits into the open end of the casing and is detachably secured therein in any suitable manner, as by means of small screws e thereby closing the 50 casing at its open end. The casing C is made suitably longer than the induction coil and thereby forms an air space E between the spark plug and the adjacent end of the induction coil and this air space communicates 55 through openings f formed in the casing with the outer air.

The shell D is provided with a hexagonal body portion for a wrench hold and it is recessed in both ends forming a dividing wall h between the two recesses.

F is a screw plug secured in a screw-threaded aperture of the dividing wall and G is an electrode formed with a conically shaped head i in which is secured the sparking point j of platinum or other suitable metal. The electrode G is wrapped lengthwise with sheet-mica held in place on opposite sides of the plug F by thin mica disks k and l which are tightly-clamped together with a clamping nut m and the locknut n placed upon the screw-threaded end of the electrode, a washer c being placed below the nut. The electrode G is electrically connected with one terminal of the secondary of the induction coil and the metallic shell of the spark plug is electrically connected with the other terminal by the binding screw p.

My construction is simple and compact and I gain the advantage of having the secondary circuit wholly internal without running the least danger of injuriously affecting the insulation of the induction coil by heat communicated from the spark plug or engine head, since it is protected by the intervening ventilated air space which extends up into the mantle and down into the spark plug, while the casing itself is a poor conductor of heat; the coil may be further protected by separating the coil from the air space by a wall H of like material and the mantle may be provided with ventilating holes for its whole length.

Having thus fully described my invention, what I claim is:

1. In an electric igniting device the combination of an induction coil, a casing of non-conducting material inclosing said coil and projecting at one end beyond the same, exterior binding screws carried by the casing in electrical connection with the terminals of the primary of the coil, a sparking plug having an exterior metallic shell forming one electrode, a second electrode insulated therein, a flanged head integral with the shell detachably engaging and closing the projecting end of the casing and forming an air space between it and the induction coil, and electrical connections connecting the exterior shell and the insulated electrode with the terminals of the secondary within the air space in the casing.

2. In an electric igniting device, the combi-

nation of an induction coil, a perforated tubular casing of non-conducting material inclosing the same and projecting at one end beyond the same, a sparking plug having one 5 electrode in the form of an exterior metallic shell secured in the projecting end of the casing, and an insulated metallic conductor secured within the shell forming the other electrode, the exterior shell forming an air space 10 between it and the induction coil and provided with an annular recess in the adjacent end of the shell around the inner electrode.

3. In an electric igniting device, a tubular casing of insulating and non-conducting material closed at the outer end, a transverse wall of insulating and non-conducting material an induction coil secured in the casing between the outer end and said transverse wall, binding screws on the outer end of the casing connected to the primary terminals of the coil, a 15 spark plug consisting of a hollow shell provided at its inner end with a circular integral

flange detachably secured in the open end of the casing and with a central dividing wall in which an insulated electrode is secured in axial coincidence with the shell, a binding post on the axial electrode securing a terminal of the secondary part of the coil extending through an aperture in the transverse wall, and a binding post in the shell securing the 20 other terminal of the secondary post likewise passing through an aperture in the transverse wall, said shell and casing being disposed to form an air chamber around the electrode and between it and the coil in communication with the outer air through apertures in the casing.

In testimony whereof I affix my signature in presence of two witnesses.

ROY E. HARDY.
